UNITED STATES PATENT OFFICE.

VICTOR EDWARD LANE, OF BERWICK, PENNSYLVANIA.

PNEUMATIC HAMMER.

No. 919,035.

Specification of Letters Patent.

Patented April 20, 1909.

Application filed April 11, 1908. Serial No. 426,461.

To all whom it may concern:

Be it known that I, VICTOR EDWARD LANE, a citizen of the United States, and a resident of Berwick, in the county of Columbia and State of Pennsylvania, have invented a new and Improved Pneumatic Hammer, of which the following is a full, clear, and exact description.

My invention relates to pneumatic hammers, the several objects of my invention being as follows: I, to promote simplicity by discarding all delicate parts, thus insuring durability under hard usage; II, to provide for a powerful down-stroke in connection with a cushioned back-stroke, thus eliminating the shock or jar so common in pneumatic hammers; III, to render the hammer, as far as practicable, independent of any specified pressure of air in order to make it operative; IV, to facilitate the removal and replacement of the barrel; V, to improve the lubrication of certain movable parts; and, VI, to hold the rivet-set securely on the end of the barrel, to prevent accidents and prevent said set from falling out.

Reference is to be had to the accompanying drawings forming a part of this specification, in which similar characters of reference indicate corresponding parts in all the figures. Figure 1 is a longitudinal central section through my improved pneumatic hammer, showing the barrel, the movable sleeve mounted therein, and the piston serving as the hammer proper and slidably mounted within the sleeve, this view also showing the arrangement of the air valve, the air in this instance being cut off; Fig. 2 is a view somewhat similar to Fig. 1, the air in this instance being turned on, this view further showing the piston as occupying a different position from that which it occupies in Fig. 1; Fig. 3 is a vertical cross section upon the line 3—3 of Fig. 1, looking in the direction of the arrow, and showing the arrangement of the barrel provided with air ducts, means for supporting the barrel, and further showing one end of the movable sleeve; and Fig. 4 is a vertical section upon the line 4—4 of Fig. 1, looking in the direction of the arrow, and showing the arrangement of the air ducts relatively to the barrel, the sleeve and the piston.

The barrel of the hammer is shown at 5 and is mounted upon a head 6 provided with a threaded collar 7 for this purpose. The head 6 is further provided with a portion 8,

serving as a handle, whereby the entire device may be manipulated. A trigger 9 is disposed within the handle and journaled upon a pivot 10. The handle is provided with a groove 11 for receiving the trigger 9 which, when forced into the groove, becomes practically flush with the inner surface of the handle.

A valve passage 12, of cylindrical form, contains a slide valve 13, the latter being provided with a stem 14, which engages the outer end of the trigger 9. A spring 17 presses against the valve 13 and tends to normally maintain it in the position indicated in Fig. 1, in which instance the valve is closed. A cap closure 15 serves to prevent undue escape of air from the passage 12 and to hold the spring 17 in place. An inlet pipe is shown at 16 and may be connected with a hose or other flexible pneumatic supply member.

The head 6 is provided with a longitudinal passage 18 and the barrel 5 is provided with a longitudinal passage 19, these passages registering with each other and being practically continuous. The barrel 5 is provided with a tool holder 20, in which is mounted a rivet-set 21, provided with a stem 22, the latter working loosely within the tool holder. A pin 23 extends diametrically through the stem 22 and has a limited play within a passage 24, this passage communicating with grooves 25 for facilitating the insertion of the pin 23.

Slidably mounted within the barrel 5 is a sleeve 26 provided externally with oil grooves 27. This sleeve 26 is further provided with a closed end 28, the latter being circumscribed by an annular passage 29, as indicated in Figs. 1 and 2. The barrel 5 is provided with a substantially U-shaped passage 30 communicating with the central passage 31 of the barrel. The sleeve 26 is provided with air passages 32 communicating with each other and merging into a general annular form, these passages being disposed in immediate proximity to the end 28. A passage 32^a extends from the central passage 31 of the barrel 5 to the passage 19 of the same, and at times registers with the passages 32, as indicated in Fig. 1. The sleeve 26 is further provided with air passages 33, 33^b 34 disposed as indicated in Fig. 1. At 33^a and 35 the barrel 5 is provided with air passages adapted to register with the passages 33^b and 34 respectively, as in

dicated in Fig. 2. The sleeve 26 is further provided with passages 36 communicating with each other and adapted to be brought into registry with a port 37, the latter being simply the inturned end of the passage 19. The barrel 5 is further provided with a passage 38 disposed adjacent to the lower or smaller end of the barrel 5. A piston 39, constituting the hammer proper, is provided with striking ends 40, 41, of reduced diameter. The barrel 5 is provided with a passage 42 (see Fig. 3) and this passage may be brought into registry with a passage 43 with which the collar 7 is provided, as indicated by dotted lines in Fig. 1 and by full lines in Fig. 3.

The rivet set 21 is normally placed loosely within the reduced portion 20 of the barrel 5 and is adapted to strike the blows when pounded by the piston 39.

The operation of my device is as follows: The air pressure is controllable by aid of the trigger 9. When this trigger is withdrawn toward the handle 8, as indicated in Fig. 2, the air is turned on full and the piston 39 has a rapid reciprocating motion. When, however, the trigger 9 is released, as indicated in Fig. 1, the air supply is cut off and the piston is motionless. Starting from the position indicated in Fig. 1, we will follow the cycle of operations. The trigger 9 is withdrawn toward the handle 8 to any desired extent, the degree of movement of the trigger directing the degree of inflow of the air, and consequently the speed and power of the hammer strokes. The valve being open and the parts being in the position indicated, the air enters through the passages 18 and 32^a, thereby starting the piston 39 into motion. As soon as this piston has traveled a distance representing its proximate length, the air behind it passes outwardly through the air passage 33 and backward through the passage 30 into the annular passage 29. This causes the sleeve 26 to move slightly, but as the weight of this sleeve is considerable and the sleeve is at first motionless, it acquires much slower motion than that of the piston 39. The forward movement of the sleeve 26, however, closes the passages 32, 32^a, 33 and 38, and opens the ports 34, 35, 36, 37, 33^a and 33^b. This, however, does not take place until after the piston 39 has practically reached the end of its stroke. The piston 55 strikes a dead blow against the stem 22 of the rivet-set. By this time (the passage 36 being in registry with the port 37), the air enters through this port and drives the piston 39 back to its starting point. During the 60 turn stroke of the piston it is subjected to a full degree of pressure until it moves far

enough to clear the port 35, but during the rest of the stroke it travels mainly by its momentum, as the air is now vented through this port. The air driven ahead of the piston 65 39 forms a cushion for the return blow and thus obviates the necessity for a severe shock. The ports 33^a and 33^b, being now in registry, cause the air in front of the piston upon the back stroke to be released. The 70 air continues to escape through the ports 33^a, 33^b, until the piston reaches these ports, the piston being cushioned during the rest of the back stroke. When the piston 39 leaves its normal position and starts toward the rivet-set, the air in front of the piston has a ready escape through the passage 38. Upon the finish of the return-stroke, however, the passages 33^a and 35 are closed, because the sleeve 26, in moving away from the rivet-set, carries the passages 33^b and 34 out of registry with the passages 35 and 33^a respectively. It will thus be seen that the piston, while moving in the proper direction to strike its blow, is uncushioned, whereas its motion in the opposite direction is cushioned.

While I show the device as equipped with a rivet-set, it will be understood that the latter may be replaced by any equivalent member. I do not limit myself to the precise construction shown for the various parts of the hammer, as they may be varied without departing from the spirit of my invention. As the rivet-set cannot be detached from the barrel except when turned into a definite position, the liability to accidents is greatly decreased. In instances where the rivet-set is perfectly loose and unconfined, an accidental or unauthorized pulling of the trigger sometimes causes the rivet-set to be forcibly ejected. This is avoided in my device.

Having thus described my invention, I claim as new and desire to secure by Letters Patent:

The combination of a barrel provided with 105 a centrally disposed passage, a sleeve mounted within said passage and slideable in relation thereto, a piston mounted within said sleeve and movable in relation to the same, said piston serving as a hammer, means for 110 applying air pressure to said piston for the purpose of propelling the same, and means for preventing escape of air during a part of the return stroke of said piston for the purpose of cushioning said return stroke thereof. 115

In testimony whereof I have signed my name to this specification in the presence of two subscribing witnesses.

VICTOR EDWARD LANE.
